CLAIM

The ornamental design for a dental instrument, as shown and described.

DESCRIPTION

1. Dental instrument

1.1: Front

1.2: Back

1.3: Left

1.4: Right

1.5: Top

1.6: Bottom

Figs. 1.1 to 1.6 are 6 views, including six orthographic projection views of a dental instrument.

The portion of the design shown in the dotted lines is for the purpose of illustrating portions of the dental instrument and forms no part of the claimed design.
